UNITED STATES PATENT OFFICE.

JOHN EDWARD WRIGHT, OF NEW YORK, N. Y.

CARD-SORTER.

1,383,891.

Specification of Letters Patent. Patented Mar. 16, 1920.

Application filed April 9, 1918, Serial No. 237,446. Renewed January 7, 1920. Serial No. 350,060.

To all whom it may concern:

Be it known that I, JOHN E. WRIGHT, a citizen of the United States, residing at New York, in the county and State of New York, have invented certain new and useful Improvements in Card-Sorters, of which the following is a full, clear, and exact description.

The invention, the subject of this application for Letters Patent, is an improvement in devices known as card sorters, which are designed to rapidly distribute to appropriate receptacles a number of cards used in computing or tabulating systems and which are distinguishable as belonging to certain classes or kinds by such indications as perforations in given positions and number.

As devices of this general character are well known in the art, and as their nature and purpose are well understood, it need only be said that the object of my improved mechanism is to pass from a pile the individual cards into a machine which will sort them according to certain distinguishing punch marks which they contain into corresponding compartments or receptacles so that all cards of a given class or kind may be assembled and inspected or utilized for purposes of computation, tabulation, or otherwise.

The improvement resides in the means which I have devised for this purpose and which may be most readily understood from the detailed description thereof which follows:

Figure 1 is a view partly in section and largely diagrammatic of the card sorting mechanism.

Fig. 2 is a front view of same apparatus. Fig. 3 is an enlarged perspective of an element of the machine to be hereinafter described.

Fig. 4 is a detail of the card distributing mechanism proper, showing it in a different position from Fig. 1 to illustrate its mode of operation.

Fig. 5 is an enlarged view in side elevation of the controlling mechanism of the sorter.

Fig. 6 is an enlarged detail of the means for controlling the permutation or combination devices.

Fig. 7 is an illustrative diagram of the possible combinations of perforations for cards, and

Fig. 8 is a circuit diagram showing the relations of the several parts and illustrating their functions.

In Fig. 1 the numeral 2 indicates a card holder containing a stack or pile of cards to be sorted and having springs 3 for pushing them forward against friction rollers 4 which are supposed to be driven by any suitable power so as to transfer the cards singly into a chute 5, which is closed at the bottom by a swinging door 6 shown in Fig. 4. The cards have in a certain part and in columns punch holes indicating by their number and position numerals, say from 1 to 0, as indicated in Fig. 7.

For example, the numerals from 1 to 4 are indicated by the vertical position of single holes 7, numerals 5 to 0 by the position of two holes, and other data if need be by three punched holes.

The cards are passed into the chute between contacts 9 and separate them, but when a card has reached the bottom of the chute 5 and rests on the closed door 6 it passes beyond the contact points 9, see Fig. 8, and permits these contacts to touch, as each card has a cut away corner 10, so that although the cards may follow one another so closely as to touch there will always be a moment when the cut away corner permits the contacts to come together.

The engagement of the contacts 9 closes the circuit of a magnet 11, which attracts its armature 13 against the force of a spring 12 and by suitable intermediate connections shifts a bar 14 carrying four pins engaging in four bars 15 to which are connected springs 16, normally under tension of the stronger spring 12, but which on the energization of the magnet 11 become themselves the master springs.

The bars 15 have racks 17, see Fig. 6, engaging with pinions 18 on pivoted plates 19, Fig. 3, and the lower edges of the plates bear upon the ends of four spring actuated rods, slidably mounted in a frame 20 and having ends arranged to extend into the path of spring seated pins *a*, also sliding in an extension of said frame 20. From this it results that while all of the bars 15 are under tension that or those only which may turn the pinions are moved and only that or those pinions which operate pins *a* which pass into holes in the card can thus turn.

The bars 15 which move carry contacts 21 thereon into engagement with stationary contacts 22 and close the circuit of one or more of the magnets 23, which control the bars 24 of what is known as a translator, the function of which is to determine which of

ten bars 25 shall fall into an open line of notches 26 in predetermined positions on said bars 24. In other words the notches are so placed that normally all of the bars 25 are retained in their raised positions by the unnotched parts of the bars 24, but when any one or more of the magnets 23 are energized the corresponding bar or bars 24 are drawn forward against the force of the springs 27, 10 with the result that under one bar 25, the notches are alined so that that bar can drop. The bars 25 are pivoted levers as shown in Fig. 5 and are moved by springs 28 connected therewith.

15 When any bar 25 moves in this way it closes an electric circuit by bringing together contacts 29 and 30, or 29 and 31, and it also forces forward a stop pin 32 into the path of a pivoted chute 33. By this means 20 any of the four levers of the group to the right when permitted to move will close the circuit of a magnet 34 and push forward its corresponding stop pin 32. While any one of the four to the left will similarly close 25 the circuit of a magnet 35 and push forward its corresponding pin 32.

Between magnets 34 and 35 is an armature lever 36 pivoted at 37 and engaging with a pin 38 on chute 33 which is pivoted 30 at 39. So therefore if one of the right hand group of bars 25 be moved this chute 33 will be swung to the right until it encounters a projecting pin 32 or if its movement be due to one of the other group of bars then it will 35 swing to the left.

The chute 33 in swinging to either right or left encounters one or the other of the arms of a fork 40 which being moved swings aside the door 6 at the bottom of the card chute 40 and thereby allows the card thereon to descend into the pivoted chute 33 and through this latter into the compartment or receptacle to which the lower end of said chute may at that moment be directed.

45 A slow acting magnet 42 which reaches its full strength later than the other magnets attracts an armature lever 43 that draws back a bar 44 and restores to its normal position that lever 25 which has been dropped 50 by the action of the translator. The apparatus is thus brought into condition to operate on another card.

The specific construction of the parts above described is not of the essence of my 55 invention and may be greatly modified providing the devices retain the functions herein assigned to them. The nature of the invention may therefore be best understood from the following summary.

60 Assume that there are a large number of differently punched cards, and that it is desired to sort them into groups corresponding to the numerals from 1 to 0, which punched holes in certain position thereon indicated.

65 These cards are run off from the pile by any

suitable means and forced between contacts 9 into the chute 5. Having reached the bottom of this chute the contacts 9 close the circuit to magnet 11, which sets the combination by means of the translator, so that the 70 pivoted chute 33 is moved to the point which will deliver the card into the receptacle corresponding to the numeral punch which it bears. As soon as this has been done the magnet 42 restores all parts of the apparatus 75 to normal position, so that the next card will fall to the bottom of chute 5 and will be forwarded in a similar manner to its proper destination.

The chief merit of this device is in its extreme simplicity. Most of the mechanisms that have been devised for a similar purpose are cumbersome, complicated and expensive, but this apparatus is one that can be built and bought for a small sum and hence it is 80 quite within the reach of small shop-keepers, manufacturers and others who may require its use.

What I claim is:—

1. In a card sorting apparatus, the combination with means for advancing a quantity of cards singly to a given position, means for operating a group of pins at the point where distinctive holes are punched in the cards, a translator operated by those pins which meet and pass through perforations, a swinging chute to receive the cards and means controlled by the translator to swing the chute to a point determined by the combination set by the punched holes 90 corresponding thereto.

2. In a card sorting apparatus, the combination with means for advancing a quantity of cards singly to a given position, a limited number of pins adapted to be moved 95 across the plane of the cards at a point where said cards carry distinctive perforations, translator bars adapted to be moved by such pin or pins as enter perforations in the card, a plurality of levers, one of which 100 is permitted to move according to the combination set up by the translator bars and means for directing the cards when released by the pins to points determined by the particular lever moved by the translator.

3. In a card sorting device, the combination with a fixed card chute having a stop therein to retain single cards in a fixed position, a swinging extension of said chute, a plurality of receptacles, a translator operated by the engagement of pins with perforations in the cards and adapted when set thereby to release a card from the main chute and direct the swinging chute to the receptacle corresponding to the combination 110 set up in the translator and the particular perforations on the cards.

In testimony whereof I affix my signature.

JOHN EDWARD WRIGHT.
